UNITED STATES PATENT OFFICE.

JOHN T. RYDBERG, OF HARRISON, NEW JERSEY, ASSIGNOR, BY DIRECT AND MESNE ASSIGNMENTS, TO SUPREME PLAYER ACTION CORPORATION, A CORPORATION OF NEW JERSEY.

AUTOMATIC CLEANER AND BRAKE FOR PLAYER ACTIONS.

Application filed March 11, 1924. Serial No. 698,441.

This invention relates to an automatic cleaner and brake for player actions, and particularly to a construction adapted for use where air tension is used for the actuation of the player elements as in piano players or pipe organs.

In this class of apparatus the constant presence of dust, lint and dirt causes the clogging of the small passages and openings, as such foreign matter is carried by the air into the pneumatic action and its collection therein prevents the free passage of the air and accurate closing of the valves, resulting in sustaining the note struck for an undesirable period.

It is also important that the cleaning of the air passages be effected in the continued use of the machine rather than at remote intervals and the most effective manner for accomplishing this during the normal use of the instrument is to remove any accumulation of foreign matter during the rewinding operation which occurs alternately with each playing action. By such an application of the cleaning device any accumulation is avoided and the mechanism maintained at its most accurate efficiency.

It is also found desirable to utilize the air tension during such cleaning operation to effect a braking action during the rewinding of the note sheet as this retards the sheet enabling the action of the cleaner through the trackerbar to remove any dust or foreign matter upon the sheet which through the braking action is rewound under tension across the tracker. The effect of this braking action is also important in rewinding the music sheet so as to effect a close and tight winding thereof upon the music roll and prevent the accumulation of slack from the take-up roll which frequently rotates more rapidly causing the sheet to feed irregularly to the music roll and as the end thereof is approached is liable to detach the connecting loop from the take-up roll so that the free end of the sheet whips across the tracker and is liable to be torn or injured thereby. As is known in ordinary practice, it is customary for the operator to use his

hand upon the music sheet to retard the feed thereof in the rewinding action and unless the sheet be tightly wound upon the music roll the latter will not properly fit the box provided for its storage and transportation.

To obviate the objections mentioned and effect a continued and desirable cleaning action, an air tension device is automatically actuated during the roll rewinding operation to pass a current of air through the passage of the pneumatic action from the trackerbar to the bleed tension chamber while the parts are in non-playing condition and simultaneously to apply a brake to the take-up roll from which the note sheet is being unwound.

The invention has for an object to provide a novel and improved construction in which the air tension for cleaning purposes is introduced into the conducting passage and bleed apertures automatically in each rewinding operation, and at which time the pouch boxes are closed by a valve against the air tension acting on the passage communicating therewith.

A further object of the invention is to provide a bleed tension chamber disposed in an accessible position at the front of the action with an air pressure connection arranged to withdraw dirt from the bleed apertures and also from the channels and openings leading to the music roll regulating apertures disposed upon the trackerbar relative to the note openings therein as the apertures leading to such channels are relatively small and liable to become clogged by lint or dirt accumulated in the continued passage of the music sheet over the trackerbar.

Another and further object of the invention is to provide a construction in which the cleaner controlling valve acts as a unit to introduce air into the passages and to actuate a pneumatic controlling a brake member for the free take-up roll.

Other and further objects and advantages of the invention will be hereinafter set forth and the novel features thereof defined by the appended claims.

In the drawings:

Figure 1 is an elevation with the parts broken away and parts of the pouch boxes in section;

Figure 2 is a detail side elevation of the pouch boxes and bleed openings;

Figure 3 is a detail section on the line 3-3 of Figure 1;

Figure 4 is a top plan of the cleaner valve;

Figure 5 is a section on the line 5-5 of Figure 4;

Figure 6 is a similar view on the line 6—6 of Figure 5;

Figure 7 is a section on the line 7—7 of Figure 6; and

5 Figure 8 is a fragmentary section showing the bleeder openings communicating with the air tension chamber.

Like numerals refer to like parts throughout the several figures of the drawing.

10 In the present application of the invention it is illustrated in connection with a pneumatic piano player action in which the music roll 10 is mounted in any desired character of support 11 and carries the music sheet 12 which is adapted to be wound upon the take-up roll 13 similarly supported in the usual manner. This music sheet cooperates with a trackerbar 14 provided with the note openings 15 and also with channels 16 having 20 apertures 17 to position and regulate the note sheet as more fully described in my prior Patent No. 1,373,100 dated March 29, 1921. The trackerbar is provided with the usual pneumatic connections which are not herein 25 shown as they comprise no part of this invention. These connections, however, communicate with a passage 18 extending to the pouch box 19 which is provided with the ordinary valve 20 controlling the passage of 30 air from the chamber 21 and also the intake 22 from the atmosphere. This pouch box communicates with a pneumatic 23 connected to the finger 24 in the ordinary manner and as indicated by dotted lines in Figure 3 35 and full lines in Figure 2.

The channel 18 communicates with a bleed tension chamber 25 through the bleed openings 26 as more specifically shown in Figure 8 and this chamber during the normal playing 40 operation of the instrument is not under tension but permits an escape of sufficient air to effect the usual restoring of the pouch box valve. The chamber 21 is also provided with an opening 27 extending from the chamber 25 and controlled by a valve member 28 such as the flap valve shown in Figure 3. For the purpose of permitting inspection of the chamber 25 and the bleed apertures communicating therewith, a face plate 29 of transparent material is secured to the main channel board 30. The arrangement of this front board 30 is particularly convenient in the construction of the pneumatic action as it permits the tube connections 31 extending 55 from the channels 18 in the tube rail 32 to the trackerbar to be concealed without the use of wings or other devices for that purpose.

For the purpose of connecting the cleaning device with the bleed chamber 25 a conduit 33 is provided and terminates in a head 34 disposed opposite an opening from the chamber 21. The opposite end of the conduit 33 communicates with a cleaner valve 35 which may be of any desired construction,

a convenient form being herein shown in Figures 4 to 7 inclusive where the base is formed with a port 36 communicating with a source of air tension as at 37 and also with a series of distributing ports 38 having passages 39 extending to the respective points of application for the air pressure during the cleaning action. The slide member 40 of this valve is mounted upon the base and guided by the side rails 41 while it is held in contact with the base by a flat tension spring 42 secured at one end to the base and bearing at its free end upon the slide 40. This slide is provided with a valve passage 43 which when shifted to the position shown in Figure 5 brings the inlet and distributing ports into communication for the purpose of applying the air tension. The slide member of the valve may be connected to the lever 44 controlling the rewinding action of the music roll by any desired means such as the rod 45 pivotally connected at 46 upon the slide 40.

Extending from two of the passages 39 are the conducting tubes 47 which communicate with the channels 16 in the trackerbar 14 before described and are so arranged as to exert a suction or vacuum action thereon which will remove dirt and lint from the music sheet passing over the bar. The remaining passage 39 communicates by a tube 48 with a pneumatic 49 connected by a rod 50 to actuate a brake 51 acting upon the end flange 52 of the take-up roll 13.

In order to establish the air tension connection with the bleed chamber a port 53 is provided at the base of one of the ports 38 and communicates with the conducting tube 33.

In order to relieve the pneumatic device 49 controlling the brake action when the cleaning valve is shifted to inoperative position the conducting passage 39 communicating with the tube 48 is provided with a bleed opening 54 as shown in Figures 4 and 5.

The operation of the pneumatic player action is as usual in this art and therefore not particularly described herein as this invention relates to the cleaning or defecating mechanism associated therewith. When the controlling valve for the cleaning connections is shifted to the position shown by full lines in Figure 1 through the operation of the re-roll lever an air tension is established in the bleed chamber which causes a closing of the valved passage to the pouch box and establishes a suction or vacuum in the ducts leading from the trackerbar note openings to the several pouch boxes. Simultaneously with such cleaning action a braking device is applied to regulate the speed of rotation of the take-up roll during such rewinding, this brake being actuated by a pneumatic connected to the unitary valve controlling means. This valve is also provided with ports in communication with the sheet con-

trolling openings which are associated with the note ducts upon the trackerbar so as to effect a cleaning action therethrough simultaneously with the movement of air through 5 the remaining ducts of the player action.

The mechanism thus provides for a defecation or cleaning of the air ducts between each playing operation and during the re-winding action all of said parts being controlled by a unitary device and operable by 10 the simple shifting of the re-roll lever. The construction and location of the bleed chamber provides for visibility of the conditions therein and disposes it at the front of the 15 action where it is easily accessible whenever necessary or desirable.

When the controlling valve is shifted to the dotted line position in Figure 1 the air tension is cut off from the bleeder chamber 20 permitting this member to operate in the usual manner while the vacuum existing in the pneumatic for the brake action is relieved by the bleeder opening provided in the communicating duct therewith. By applying 25 the tension of the air pressure opposite to the bleed openings any lint or dust entering through the channels of the trackerbar is prevented from settling against or in the bleeds and they are thus automatically 30 cleaned and the most efficient operation maintained. The valve mechanism provided forms a unitary controlling means for the air tension applied for cleaning the several parts and effects a simultaneous operation 35 in order to effect a thorough defecation during the short period of the rewinding action.

While the details of the invention have been specifically shown and described, changes and alterations may be made there- 40 in without departing from the spirit of the invention as defined by the appended claims.

Having thus described my invention, what I claim as new and desire to secure by Letters Patent is:

- 45 1. In a piano cleaning mechanism, a trackerbar and air passage therefrom to a pouch box, winding rolls for a music sheet cooperating with said bar, a normally inactive cleaning duct independent of said passage to the trackerbar and communicating therewith at said box, and means operable in the change of winding direction of the rolls to apply air tension to the cleaning duct.
- 55 2. In a piano cleaning mechanism, a trackerbar and air passage therefrom to a pouch box, winding rolls for a music sheet cooperating with said bar, a normally inactive cleaning duct independent of said passage to the trackerbar and communicating therewith at said box, and a manually operable valve connected to the roll winding means to apply air tension to the cleaning duct when the winding direction of the rolls 60 is changed.

3. In a piano cleaning mechanism, a trackerbar and air passage therefrom to a pouch box, winding rolls for a music sheet cooperating with said bar, a normally inactive cleaning duct independent of said passage to the trackerbar, a bleed chamber communicating with said duct and pneumatic, and manually actuated means for applying an air tension through said duct to create a current from the trackerbar to the bleed 70 chamber and cleaner duct.

4. In a player action, the combination with a music roll and take-up roll, a trackerbar intermediate of said rolls, of a braking device applicable to the take-up roll, means for applying an air tension to clean the passages of said action, a pneumatic for actuating said brake, and means for controlling said pneumatic coincident to the application of air for cleaning purposes. 80

5. In a player action, the combination with a music roll and take-up roll, a trackerbar intermediate of said rolls, of a braking device applicable to the take-up roll, means for applying an air tension to clean 90 the passages of said action, a pneumatic for actuating said brake, means for controlling said pneumatic coincident to the application of air for cleaning purposes, and a connection from said controlling means to sheet 95 regulating apertures disposed upon said trackerbar.

6. In a player action, the combination with a music roll and take-up roll, and an intermediate trackerbar, of a braking device applicable to the take-up roll, a pneumatic for actuating said brake, a controlling valve communicating with said pneumatic, and a connection from a rewind control lever to said valve. 100

7. In a player action, the combination with a music roll and take-up roll, and an intermediate trackerbar, of a braking device applicable to the take-up roll, a pneumatic for actuating said brake, a controlling valve communicating with said pneumatic, a connection from a rewind control lever to said valve, a pouch box and bleed chamber connected thereto, and a communicating passage from said valve to the bleed chamber. 110

8. In a player action, the combination with a music roll and take-up roll, and an intermediate trackerbar, of a braking device applicable to the take-up roll, a pneumatic for actuating said brake, a controlling valve communicating with said pneumatic, a connection from a rewind control lever to said valve, a pouch box and bleed chamber connected thereto, a communicating passage from said valve to the bleed chamber, and a communication from said valve to sheet 120 controlling apertures in the trackerbar.

9. In a piano cleaning mechanism, a trackerbar and air passage therefrom to a pouch box, winding rolls for a music sheet 130

cooperating with said bar, a normally inactive cleaning duct independent of said passage to the trackerbar, a bleed chamber communicating with said duct and pneumatic, 5 a source of air tension, and a valve device having ports communicating with said tension and the trackerbar passages and cleaning duct, said device being shiftable to cut off tension to the cleaner duct when winding and apply such tension thereto when rewinding.

10. In a player action, a pouch box, a trackerbar, an air duct connecting said parts, a bleeder chamber connecting with 15 said duct, a valve controlling an opening from said bleeder chamber to said pouch box adapted to be closed during the cleaning action, and means for establishing an air suction in said chamber.

11. In a player action, a pouch box, a trackerbar, an air duct connecting the same, a bleeder chamber having an aperture communicating with said duct, a transparent plate forming a wall of said chamber disposed opposite said aperture to permit visibility thereof, and means for establishing an air tension in said chamber.

12. In a player action, a pouch box, a trackerbar, an air duct connecting the same, 30 a front board provided with a bleed chamber and communicating passage to said pouch box, and a channeled top board communicating with the passage in the front board and with the duct to the trackerbar.

13. In a player action, the combination

with a music roll and take-up roll, of a brake device cooperating with the latter, a pneumatic connected to said device for maintaining it in contact with the take-up roll when subjected to suction, and means for relieving the suction within the pneumatic to release the brake.

14. In a player action, the combination with a trackerbar and pouch boxes, ducts communicating between the trackerbar and pouch boxes, a valve having ports communicating with the trackerbar, an independent port communicating with the ducts to the pouch box, a sliding member for said valve adapted to simultaneously establish 50 communication between all of said ports, a brake device adapted to cooperate with a winding roll, and a pneumatic therefor communicating with a port in said valve disposed for simultaneous communication with 55 the air tension when the valve is in operative position.

15. In a player action, the combination of a trackerbar having note ducts and sheet regulating openings, a pouch box, a channel 60 communicating from said pouch box to said note ducts, a bleed chamber communicating with said channel, a cooperatively driven music roll and take-up roll, a brake mechanism operative upon said take up roll, and 65 a unitary device for controlling the application of air tension to the trackerbar, brake mechanism and passages to the pouch box.

In testimony whereof I affix my signature.
JOHN T. RYDBERG.
